(57) **CLAIM**

The ornamental design of a brake heat sink, as shown and described.

DESCRIPTION

FIG. 1 is a perspective view of a brake heat sink showing my new design with environmental structure;

FIG. 2 is another perspective view of a brake heat sink showing my new design;

FIG. 3 is a top plan view of a brake heat sink;

FIG. 4 is a bottom plan view of a brake heat sink;

FIG. 5 is a right-side view elevational of a brake heat sink;

FIG. 6 is a left-side elevational view of a brake heat sink;

FIG. 7 is a front elevational view of a brake heat sink; and,

FIG. 8 is a rear elevational view of a brake heat sink.

The broken line structure shown in FIG. 1 is for illustrative purposes only and form no part of the claimed design.
